HEMMING ATTACHMENT FOR SEWING MACHINES

John P. Enos, Union, N. J., assignor to The Singer Manufacturing Company, Elizabeth, N. J., a corporation of New Jersey

Application November 15, 1950, Serial No. 195,791

9 Claims. (Cl. 112—143)

1

This invention relates to hemming attachments for sewing machines and more particularly to a narrow-hem forming attachment of the type having a pair of complementary spiral scroll-members for hem-folding the margin of a necktie or handkerchief and directing the hem-folded margin to the needle of a sewing machine.

The present prevalent use of relatively stiff or wiry fabrics in the manufacture of neckties presents a difficult problem in the production of narrow uniform hems along the edge of the material. This type of fabric being quite stiff or wiry does not readily crease or fold and, as a consequence, it tends to slip laterally out of the usual type of hemmer employed for producing necktie hems. Thus, an improperly folded hem is presented to the stitching instrumentalities of a sewing machine with the result that the marginal edge of the fabric is exposed rather than being hidden from view within the body of the hem.

It is, therefore, the primary object of the present invention to provide a scroll hemmer with means for insuring that the work to be hemmed will not shift laterally of the unit during its passage longitudinally therethrough.

The foregoing, and other objects and advantages in view, together with means whereby the same may be carried into effect, will thus be understood from the following description of a preferred embodiment of the invention illustrated in the accompanying drawings, in which:

Fig. 1 represents a side elevation of a scroll hemmer embodying the present invention.

Fig. 2 represents a top plan view of the scroll hemmer illustrated in Fig. 1.

Fig. 3 represents a top plan view of the base plate of the present attachment.

Fig. 4 represents a top plan view of the primary scroll member.

Fig. 5 represents a top plan view of the secondary scroll member.

Fig. 6 represents a top plan view of an auxiliary arm member.

Fig. 7 represents a right-hand side view of the auxiliary arm shown in Fig. 6.

Fig. 8 represents a front elevation view taken substantially along the line 8—8 of Fig. 2, and illustrating the manner in which the work progresses through the hemmer unit.

Fig. 9 represents a vertical sectional view through the work as it progresses through the exit end of the present unit.

Fig. 10 represents a vertical sectional view through the work as it progresses through the

2

usual type of hemmer, and it illustrates the manner in which a stiff fabric tends to resist creasing or folding.

Referring more in detail to the drawings, the 5 hemming attachment comprises a base-plate 10 fitted at one end with the usual depending fastening screw 11 which is adapted to project through a suitable hole in the bed-plate of a conventional sewing machine and have threaded upon it a clamping nut (not shown) for holding the hemmer in operative position. At its other end, the base-plate 10 is formed with a down-turned lip 12 which is adapted to extend into a locating hole in the usual sewing machine throat-plate to assist in maintaining the hemmer in proper alignment with the sewing machine stitching devices.

Adjustably mounted on the base-plate 10 is the shank 13 of a primary scroll member 14; the shank 13 being formed with an elongated hole 15 through which extends a clamping screw 16 threaded into a reinforced portion 17 of the base-plate 10. The elongated hole 15 and the clamping screw 16 provide means for permitting adjustment of the hemmer toward and from the stitching devices of a sewing machine. At its rear end, the shank 13 is preferably bent downwardly, as at 18, to rest substantially, when not in use, upon the usual cloth-plate of the sewing machine to provide an inclined guiding surface facilitating the introduction of work into the mouth of the hemmer. Substantially midway of its length the primary scroll-member 14 is formed with a lateral extension 19 providing a fulcrum support for the overlying shank 20 of a secondary scroll member 21 spiraled in conformity with the primary scroll-member 14 to define a fabric passageway 22 (see Fig. 1) extending from the receiving end or mouth 23 to the delivery end 24 of the attachment.

It is to be particularly noted that the free end portions of each of the primary and secondary scroll hemmers is formed as a substantially flat tongue 14' or 21' and it will be observed particularly from Fig. 8 that these tongues are disposed one above the other in substantially parallel relation.

For securing the secondary scroll member 21 to the primary scroll member 14, a screw 25 is provided which passes through an aperture 26 formed in the shank member 20 of the primary scroll so as to be threaded into an aperture 27 formed within the shank portion 19 of the primary scroll 14. It is to be particularly noted that the secondary scroll aperture 26 is elongated

in a lateral direction so as to permit the secondary scroll member to be bodily shifted laterally of the primary scroll member 14 with the result that the capacity of the hemmer unit is varied. In other words, this relative shifting of the two scroll members results in a change of the capacity or size of the fabric passageway defined by the two scroll members 14 and 21. The screw 25, however, when secured properly within the threaded aperture 27, effectively locks the primary and secondary scroll members in any one of a plurality of selected positions.

Pivottally mounted upon the scroll member shank 20 by means of a screw 28 is a flat base portion 29 of an auxiliary support of which the arm portion 30 extends from the base 29 to terminate in a flat finger element 31 which normally underlies the tips or tongues 14' and 21' of the scrolls so as to bias the two scroll tongues together. As is particularly noted in Figs. 6 and 7, the right-hand edge portion of the finger 31 is bent upwardly, as at 32, thereby to form an abutment member which functions to engage the folded edge of the work-piece for the purpose of preventing the work from shifting laterally relative to the scroll tongues. The work is further prevented from shifting laterally relative to the scrolls by reason of the fact that the scroll tongues are biased together by the finger member 31. For pivotally securing the auxiliary member to the shank portion 20 of the secondary scroll 21, the screw 28 passes through an aperture 33 formed in the auxiliary member and is threadedly received within an aperture 34 formed within a thickened portion of the secondary scroll-member shank 20. Clearly, this pivot screw permits the arm member 30 to swing about the screw or stud 28 so that the finger and abutment elements 31 and 32 may be swung to and from the scroll tongues. Upon tightening the screw 28 the auxiliary member or arm 30 will be locked in any one of a plurality of selective positions. Formed upon the base portion of the auxiliary member is an upstanding lip or arm 35 which functions as a finger-piece to permit the operator to swing the arm 30 with facility whenever the screw 28 is loose.

Referring particularly to Fig. 8, it will be observed that the finger element 31 of the auxiliary arm is normally disposed below the tongue elements of the primary and secondary scroll members so as to bias these two tongues together thereby to prevent the selvedge edge portion 36 of the work from shifting laterally between the two opposing tongue portions. It will also be observed that the abutment member 32 extends adjacent the corresponding edge portions of the two tongues so as to engage the work and force the same into intimate contact with the tongue elements to the end that the work is prevented from shifting laterally away from the opposed tongue elements. As hereinabove noted, experience has indicated that wiry fabrics are difficult to hem for the reason that such fabrics are not readily folded or creased, and as a consequence they tend to shift out from between the tongues of the usual folder. The finger and abutment elements 31 and 32 of the present device, however, overcome this tendency of such stiff materials. Still referring to Fig. 8, it will be observed that the free end portion of the arm 30 is shaped substantially as an L with the above noted finger element 31 forming the lower or horizontal limb of the L while the other abutment member 32 forms the vertical limb of such

L. It is also to be understood that the arm 30 is in the form of a leaf-spring of which the end portion carries the elements 31 and 32 with the element 31 being biased normally upwardly against the free end portion or tongue of the primary scroll 14 which, in turn, is biased upwardly against the corresponding tongue of the secondary scroll member 21. Experimentation has indicated that either of the finger or abutment elements 31 and 32, if used separately in conjunction with a hemmer of the present type, has a beneficial effect so far as the production of hem work is concerned. However, experience also indicates that the combination of the finger and abutment elements 31 and 32 working in concert with such a binder materially increases the beneficial results obtained.

In Fig. 9 there is illustrated a vertical sectional view through the work as it passes longitudinally through the present hemmer, and it will be observed that the selvedge edge portion 36 of the work is maintained directly within the body portion of the hem so that as a needle 37 penetrates the work it will effectively puncture both the body portion of the work as well as the marginal portion and the bottom portion of the hem. Thus, a seam will be properly secured within all layers of the hem.

Referring now to Fig. 10, there is illustrated a vertical sectional view through a piece of work as it progresses longitudinally through the usual type of hemmer, and it is to be observed that the selvedge or marginal edge portion 36 of this work has moved laterally of the hemmer to a degree such that it would be impossible for the needle 37 to penetrate such portion and as a consequence an improper or faulty hem would be produced. By employing, however, the present invention which comprises the auxiliary arm 30, together with its finger and abutment elements 31 and 32 in conjunction with a scroll hemmer of the present type, it is found that the abutment and finger elements effectively prevent a stiff or wiry fabric from shifting laterally of the scroll members to the end that a proper hem is formed.

Being carried by the secondary scroll-member 20, the arm 30 partakes of any adjustments effected of the member 20, thus maintaining the preset relationship of the finger-elements 31, 32 with respect to the hemmer-scrolls. However, the arm 30 may be adjusted independently of the member 20 to vary the effective position of the elements 31, 32.

Having thus set forth the nature of the invention, what I claim herein is:

1. A hemming attachment for sewing machines comprising, a longitudinally spiraled primary scroll-member having its free end portion formed as a substantially flat elongated tongue, a longitudinally spiraled secondary scroll-member complementary to said primary scroll-member in defining a passageway therebetween and having its free end portion formed as a substantially flat elongated tongue which is disposed adjacent and substantially in parallelism with the first mentioned tongue, and an abutment element disposed adjacent two corresponding side edges of and bridging the passageway defined between said two tongues for engaging the work material and forcing the same to wrap intimately about said two side edges.

2. A hemming attachment for sewing machines comprising, a base-plate, a longitudinally spiraled primary scroll-member supported by said base-plate and having its free end portion formed as

a substantially flat elongated tongue, a longitudinally spiraled secondary scroll-member supported by said base-plate in complementary relation with said primary scroll-member so as to define a passageway therebetween and having its free end portion formed as a substantially flat elongated tongue which is disposed adjacent and substantially in parallelism with the first mentioned tongue, an abutment element disposed adjacent two corresponding side edges of and bridging the passageway defined between said two tongues for engaging the work material and forcing the same to wrap intimately about said two side edges, and an arm in the form of a leaf spring extending alongside of said scroll-members with one end portion thereof carrying said abutment element and with its other end supported by said base-plate.

3. A hemming attachment for sewing machines comprising, a base-plate, a longitudinally spiraled primary scroll-member supported by said base-plate and having its free end portion formed as a substantially flat elongated tongue, a longitudinally spiraled secondary scroll-member supported by said base-plate in complementary relation with said primary scroll-member so as to define a passageway therebetween and having its free end portion formed as a substantially flat elongated tongue which is disposed adjacent and substantially in parallelism with the first mentioned tongue, a finger element disposed adjacent the flat face of one of said tongues and normally engaging such surface for biasing such tongue toward the other, an abutment element disposed adjacent two corresponding side edges of and bridging the passageway defined between said two tongues for engaging the work material and forcing the same to wrap intimately about said two side edges, and an arm extending alongside of said two scroll-members and having its one end portion carrying said finger and abutment elements and having its other end supported by said base-plate.

4. A hemming attachment for sewing machines comprising, a base-plate, a longitudinally spiraled primary scroll-member supported by said base-plate and having its free end portion formed as a substantially flat elongated tongue, a longitudinally spiraled secondary scroll-member supported by said base-plate in complementary relation with said primary scroll-member so as to define a passageway therebetween and having its free end portion formed as a substantially flat elongated tongue which is disposed adjacent and substantially in parallelism with the first mentioned tongue, a substantially L-shaped member disposed adjacent said two tongues with one limb of the member extending beneath one tongue and normally biasing such tongue toward the other tongue and with its other limb disposed adjacent two corresponding edge portions of said two tongues for engaging the work material and forcing the same to wrap intimately about said two side edges, and an arm having one end carrying said L-shaped member and its other end supported by said base-plate.

5. A hemming attachment for sewing machines comprising, a base-plate, a longitudinally spiraled primary scroll-member supported by said base-plate and having its free end portion formed as a substantially flat elongated tongue, a longitudinally spiraled secondary scroll-member supported by said base-plate in complementary relation with said primary scroll-member so as to define a passageway therebetween and having its

free end portion formed as a substantially flat elongated tongue which is disposed adjacent and substantially in parallelism with the first mentioned tongue, a substantially L-shaped member disposed adjacent said two tongues with one limb of the member extending beneath one tongue and normally biasing said tongue toward the other tongue and with its other limb disposed adjacent two corresponding edge portions of said two tongues for engaging the work material and forcing the same to wrap intimately about said two side edges, an arm in the form of a leaf spring having one end carrying said L-shaped member and its other end supported by said base-plate, and pivot means interposed between said arm and said base-plate so that said L-shaped member can be swung away from said tongues.

6. A hemming attachment for sewing machines comprising, a longitudinally spiraled primary scroll-member having its free end portion formed as a substantially flat elongated tongue, a longitudinally spiraled secondary scroll-member complementary to said primary scroll-member in defining a passageway therebetween and having its free end portion formed as a substantially flat elongated tongue which is disposed adjacent and substantially in parallelism with the first mentioned tongue, and a finger element disposed adjacent the free end portion of said two scroll-members and engaging the flat face of one of said tongues for biasing such tongue toward the other.

7. A hemming attachment for sewing machines comprising, a base-plate, a longitudinally spiraled primary scroll-member supported by said base-plate and having its free end portion formed as a substantially flat elongated tongue, a longitudinally spiraled secondary scroll-member supported by said base-plate and complementary to said primary scroll-member in defining a passageway therebetween and having its free end portion formed as a substantially flat elongated tongue which is disposed adjacent and substantially in parallelism with the first mentioned tongue, a finger element disposed adjacent the free end portion of said two scroll-members and engaging the flat face of one of said tongues for biasing such tongue toward the other, and an arm having one end carrying said finger and its other end supported by said base-plate.

8. A hemming attachment for sewing machines comprising, a base-plate, a longitudinally spiraled primary scroll-member supported by said base-plate and having its free end portion formed as a substantially flat elongated tongue, a longitudinally spiraled secondary scroll-member supported by said base-plate and complementary to said primary scroll-member in defining a passageway therebetween and having its free end portion formed as a substantially flat elongated tongue which is disposed adjacent and substantially in parallelism with the first mentioned tongue, a finger element disposed adjacent the free end portion of said two scroll-members and engaging the flat face of one of said tongues for biasing such tongue toward the other, an arm in the form of an elongated flat spring disposed at one side of said two scroll-members with one end portion thereof supported by said base-plate and with its other end carrying said finger, and pivot means interposed between said base-plate and said arm so that said finger may be shifted away from the free end portions of said scroll-members.

9. A hemming attachment for sewing machines comprising, a longitudinally spiraled primary scroll-member having its free end portion formed as a substantially flat elongated tongue, a longitudinally spiraled secondary scroll-member complementary to said primary scroll-member in defining a passageway therebetween and having its free end portion formed as a substantially flat elongated tongue which is disposed adjacent and substantially in parallelism with the first mentioned tongue, a finger element disposed adjacent the free end portions of said two scroll-members and engaging the flat face of one of said tongues for biasing such tongue toward the other, and an abutment element disposed adjacent two corresponding side edges of and bridging the

passageway defined between said two tongues for engaging the work material and forcing the same to wrap intimately about said two side edges.
